UNITED STATES PATENT OFFICE.

LEWIS S. BORTREE, OF TOLEDO, OHIO.

CORSET.

SPECIFICATION forming part of Letters Patent No. 248,281, dated October 18, 1881.

Application filed May 17, 1881. (Model.)

To all whom it may concern:

Be it known that I, LEWIS S. BORTREE, of Toledo, Lucas county, Ohio, have invented an Improvement in Corsets, of which the following is a specification.

The nature of this invention relates to new and peculiar improvements in the construction of corsets, whereby the same are made adjustable around the body, and also adjustable vertically, to adapt them to wearers of different conformation of bust; and the invention consists in the peculiar construction of parts and their combination, as more fully hereinafter set forth.

15 In the accompanying drawing, which forms a part of this specification, and in which my improved corset is shown in perspective, A represents the rear half of the side section, and B the front half of the same, the piece A being secured to the back pieces of the corset, and the piece B to the front section of the corset, in the usual manner.

25 The adjoining edges of the pieces A B are provided with a series of eyelets, *a*, placed near together for the purpose of securing such edges as firmly together by lacing as they would be if joined together by a seam. The upper portion of the edges is provided with another series of eyelets, *b*, at farther distances apart, by 30 means of which and a suitable and separate lacing the upper end of the corset may be adjusted to greater or lesser busts.

It will be noticed that the series of eyelets *a* in the piece A extend below the lacing, as 35 shown, and the eyelets *a* in the piece B extend above the lacing, as shown. The object of this is to allow the back of the corset to be adjusted to a higher or lower plane with relation to the

front as may be required by the differences in form of those who otherwise wear the same 40 size of corset.

The piece B is cut away at its bottom in curved lines, as shown, thereby forming a small opening to embrace the front portion of the hip, while the piece A extends downward immediately over the center and rear portion of the hip-joint, and the two pieces A B are adjustably secured together by means of an adjusting strap, C. The piece A is vertically boned from top to bottom in the usual way, and 50 the piece B is similarly boned from top to bottom, each bone, however, being longer than the adjacent one in the series, and with their lower ends terminating upon the curved bottom of this portion of the corset, where they are secured in any suitable manner.

It will be found that in a corset of this construction a greater variety of forms may be fitted with the same size corset than with any of the known constructions, as the back and 60 front may be vertically adjusted with relation to each other, while at the same time the bottom and top may be readily adjusted to varying sizes of busts and hips.

What I claim as my invention is—

In a corset, the separate side pieces, A B, the piece B being cut away at its lower end to leave an opening between the two pieces, in combination with a strap for adjusting the size of the opening between the pieces at the lower 70 end, and separate means of adjusting said pieces above the strap, substantially as described.

LEWIS S. BORTREE.
